RODLESS PUMP

Walter N. Huff, Harwood, Tex.

Application May 21, 1936, Serial No. 81,111

2 Claims. (Cl. 103—44)

This invention relates to pumps, especially those used in oil wells and the object thereof is to produce a pump of simple construction, which is durable and efficient in operation.

5 One object of the invention is to eliminate the use of long lifting rods which in wells of great depth are a great disadvantage.

Another object of the invention is to use pressure generated by a pump at the surface to compress a spring at the bottom of the well and use the energy of expansion thus stored in the spring to force the fluid above the surface. Other objects will appear from the following description.

This application is directed to improvements in 15 the devices shown in applicant's co-pending applications Ser. No. 64,920 filed February 20, 1936, now abandoned; Ser. No. 44,114 filed Oct. 8, 1935, now Patent No. 2,058,455, dated Oct. 27, 1936; Ser. No. 80,211 filed May 16, 1936; and Ser. No. 20 20 81,110 filed May 21, 1936 now Patent No. 2,095,602, dated Oct. 12, 1937.

The invention will be clearly understood from the following detailed description, taken in connection with the drawing, in which:

25 Fig. 1 is a vertical cross-section with parts shown in elevation.

Fig. 2 is a cross-section looking in the direction of the arrows on line 2—2 of Fig. 1.

Fig. 3 is a cross-section looking in the direction of the arrows on line 3—3 of Fig. 1.

The tubing reaching from the surface to a short distance above the bottom of the well is designated by the numeral 1.

A cylinder 8, hereinafter called the pressure cylinder, of substantially less cross-section area than the tubing, is attached to the lower end of said tubing and to the lower end of said cylinder, 8, is attached another cylinder 2, hereinafter called the pumping cylinder, of substantially the 35 same diameter as the tubing, or in all cases of greater cross-sectional area than pressure cylinder 8. These attachments may be made as shown by a screw-threaded annulus or any preferred fluid-tight means.

40 45 To the lower end of this cylinder 2 is connected, by means of a flanged stop collar 4, a perforated cylinder 5 to the lower end of which a second flanged collar 6 is attached as by screw-threads. All of said collars are internally screw-threaded 50 at each end as shown for attachment of the parts and each of the stop collars has an internal flange for a purpose to be described later. To the bottom collar 6 is attached any desired footing. At the top of the tubing 1 is secured a cap 7 having an internally screw threaded aperture therein.

Within the pressure cylinder 8 is a fluid tight valved piston 10 slidable in the cylinder 8. The check valve 10' closing the central opening in this piston is confined by a cage as shown. Attached to this piston preferably by means of a cage 5 structure as shown is a rod 11 extending into the pump cylinder 2. A cage 12 is attached to the lower end of said rod 11 and to a valved piston 13 capable of sliding fluid-tight in said pump cylinder. A check valve 14, opening upwardly is 10 confined by the cage 12 and when seated closes the aperture in valve piston 13.

A second cage 15 is attached to the bottom of the piston and to this second cage a preferably hollow lifting rod 16 is attached. While 15 these various attachments are shown as formed by screw threads, any equivalent means of attachment may of course be used.

The lifting rod passes through the collar 4 and well down into the perforated cylinder 5. On this rod within the perforated cylinder is screwed or otherwise fixedly attached, a perforated washer 17 shown in detail in Fig. 3.

A strong heavy coil spring 18 is confined within the perforated cylinder and bears against the 25 perforated washer at one end and an inwardly extending flange on the collar 6. As this spring reacts with great force after compression, a light cushioning spring 19 is confined in the upper portion of the perforated cylinder bearing on 30 the washer 17 and preferably attached thereto and bearing on the other end, at least when compressed, on the flange of the collar 4.

The apparatus for applying pressure to the fluid in the tube 2, releasing said pressure and 35 affording delivery to the oil is above the surface of the ground, and will now be described. This apparatus comprises a pump 20, single or multiplex and operated by a source of power not shown.

40 The pump has an accumulator 21 and a supply pipe 22 leading from a source of supply 23.

The accumulator may be of any type and may comprise weights lifted by the pressure of air confined and compressed by the liquid operated 45 on by the pump.

Communicating with the accumulator is a pipe 25 leading to a valve casing 26, having three lateral openings and a revoluble three-way valve 27 therein for putting desired openings in communication with each other.

The lower opening of said valve casing has attached thereto a pipe 28, the lower end of which is attached to the cap 7. The tubing 1 is thus in communication with the pump and 55

5 accumulator in one position of the valve, the delivery being shut off, while in another position, as shown, the tubing 1 is in communication with the delivery pipe 29, leading to a storage tank 30.

10 The three-way valve is automatically turned through ninety degrees by any convenient mechanism as a link connection 31 shown, or a cam, actuated by any convenient source of power.

15 The pump may be, but is not necessarily, used for this purpose. T's 32 and 33, respectively, forming parts of pipes 25 and 28 serve to connect a by-pass 34 to said pipes. A check valve 35 opening upwardly in the by-pass serves to 20 correct any tendency to a vacuum above the three-way valve.

The operation of the device is as follows:

20 After some strokes of the pump the pressure rises, the valve 27 is automatically turned to place tubing 1 and the accumulator in communication, the delivery being thereby shut off.

25 The fluid pressure acting on the piston 10 forces the same downward and holds valve 10' closed thus cutting off communication between the tubing 1 and the cylinders below.

30 As the piston 10 descends, fluid must enter the tubing from the source of pressure and the volume of that fluid will be the internal cross-section of the pressure cylinder 8 multiplied by the vertical movement of the piston 10. Piston 13 is moved downwardly through the same distance as piston 10. Valve 14 is raised and fluid flows into the upper part of pumping cylinder 2. The volume of fluid thus entering the upper part 35 of pumping cylinder 2 is equal to the internal cross-section of the cylinder 2 multiplied by the distance through which the piston 13 moves which is equal to the distance through which the piston 10 moves.

40 At the end of the downward stroke the volume of fluid above the piston 13 is increased by the difference between the aforesaid volumes. Through rod 16 and washer 17, spring 18 in the perforated cylinder 5 has been compressed by the downward movement of piston 10.

45 The pressure on the fluid at the surface of tubing 1 is automatically released by oscillating the valve to close the communication with the source of pressure and open the communication with the delivery.

50 The energy stored in the spring 18, raises the washer 17 and the piston 13. The valve in the piston 13 closes, valve 10' opens and fluid is

forced through the delivery pipe. As the piston 13 reaches the upper limit of its stroke, valve 27 is oscillated to close communication with the delivery pipe and open communication with the source of pressure. The cycle of operations is 5 then repeated.

10 In the operation of this device the fluid below the pumping piston is never subjected to the pressure of the pressure source and hence oil from the well may flow freely into the perforated cylinder to take the place of that removed. Moreover, largely owing to this fact, the casing usually in the well may if desired, be dispensed with.

15 Having fully described my invention and the operation thereof, what I claim is:

1. In a pumping apparatus, a fluid-tight tubing, means connecting the upper portion of said tubing alternately to a source of fluid pressure and to the atmosphere, a pressure cylinder of substantially less diameter connected to the lower 20 end of said tubing, a piston having an aperture therein slidable in said cylinder, a check valve for closing said aperture on upward movement of said piston, a pumping cylinder of substantially greater diameter than said pressure cylinder secured to the lower end of said pressure cylinder, a valved pumping piston in said pumping cylinder, a rod connecting said pistons, a perforated cylinder, a collar securing said perforated cylinder to the lower end of said pumping 30 cylinder, a lifting rod secured to said pumping piston and extending into said perforated cylinder, a perforated washer fixed on said lifting rod, a flanged collar fitted to the lower end of said perforated cylinder, a heavy spring surrounding 35 the lower part of said rod and bearing at one end against the flange on the lower collar and on the other end against the washer whereby on alternately opening communication with the source of fluid pressure and with the atmosphere 40 fluid will be pumped from the tubing.

2. The device as claimed in claim 1 wherein the source of fluid pressure comprises a pump and an accumulator and the means connecting the tubing alternately to the source of fluid pressure and to the atmosphere comprises piping, a three-way valve in said piping and means for oscillating said three-way valve to open it to the source of pressure and the tubing, closing it to the atmosphere and to close it to the source 45 of pressure and open it to the atmosphere and the tubing.

50 WALTER N. HUFF.
